[57] **ABSTRACT**

A self-closing automatic umbrella of the type which can be opened from a closed position to an umbrella erect position by applying pressure to the end of the stick to telescope the umbrella stick, such as pressing the stick against the ground and which can be closed by releasing a suitable release. An independent locking device is provided for locking the stick in a stick extended position so that the umbrella, when closed, can be used as a walking stick and whereby the independent locking device can be released to allow the umbrella stick to be telescoped for opening the umbrella.

SHEET 2 OF 2

SELF-CLOSING UMBRELLA FRAME

BACKGROUND OF THE INVENTION

1. Field of the Invention

The present invention relates to an umbrella frame and more particularly to an umbrella frame which can be opened and closed automatically in relation to the telescoping and extending of the telescopic stick.

2. Description of the Prior Art

Self-closing umbrellas of this type have been proposed as illustrated by U.S. Pat. No. 3,003,508, issued Oct. 10, 1961, to Fritz Bremshey. In this type of umbrella, the dome ribs and canopy are open to an umbrella erect position by pressing the tip against a fixed object, such as the ground, causing the telescopic stick to shorten and compress the compression spring within the stick to load the umbrella stick when it is telescoped. The action of telescoping the umbrella stick forces the dome ribs to open to an umbrella erect position, since the crown and the runner are fixed to different telescopic parts of the stick. When it is required to close the umbrella, a release catch is merely depressed which allows the loaded spring to extend the telescopic parts of the stick, thereby forcing the dome ribs to close.

However, in the self-closing umbrellas of this type, the umbrella stick could be accidentally telescoped, thereby opening the dome ribs when it is pressed against any fixed object. For instance, if someone is walking along a sidewalk and naturally using the umbrella as a walking stick, the telescopic stick sections would telescope partially every time the tip is pressed against the sidewalk. This, of course, is a disadvantage since it is natural for someone to use an extended umbrella as a walking stick when the umbrella is not in use.

SUMMARY OF THE INVENTION

An aim of the present invention is to provide an improved self-closing umbrella of the type which is opened by telescoping the umbrella stick, wherein a separate locking device is provided for retaining the umbrella stick in an elongated extended locked position when the umbrella is closed and not being used as such in order to allow the umbrella to be used as a walking stick and to prevent the dome ribs from opening accidentally as the tip is being pressed against the ground.

A further aim of the present invention is to provide such an umbrella wherein no additional controls are necessary, but wherein the separate locking device is controlled remotely by a single actuating control device.

A construction in accordance with the present invention includes an umbrella having an umbrella stick, with at least two telescopic sections and compression spring means provided between the sections, a first locking means for locking the umbrella stick sections in their telescoped loaded position, control means for disengaging the locking means to unlock the stick sections and allow the sections to extend, second locking means adapted to lock the umbrella stick sections when the stick sections are in their extended position, and connecting means between said control knob and said second locking means for disengaging said locking means to allow the umbrella stick sections to telescope

when a preselected force is applied to the umbrella stick.

BRIEF DESCRIPTION OF THE DRAWINGS

The invention will now be described in detail having reference to the accompanying drawings, wherein:

FIG. 1 is a side view of an umbrella frame in its umbrella stick extended position whereby the dome ribs are closed;

FIG. 2 is an enlarged fragmentary view of the umbrella stick shown partly in cross section to illustrate details of the stick;

FIG. 3 is an enlarged fragmentary view of the stick similar to FIG. 2, but with the details in a different operative position;

FIG. 4 is an enlarged fragmentary view of the umbrella stick as shown in FIGS. 2 and 3 and showing the details in a still further different operative position;

FIG. 5 is a radial cross section taken along lines V—V of FIG. 2; and

FIG. 6 is a radial cross section taken along lines VI—VI of FIG. 2.

DESCRIPTION OF THE PREFERRED EMBODIMENTS

The umbrella will now be described in more detail with specific reference to FIG. 1. The umbrella is shown having a telescopic umbrella stick 1 made up of stick section 2 and stick section 3. Stick section 2 as shown in FIG. 2 includes a hexagonal cross section adapted to slide in the normally cylindrical section 3 which is provided with a hexagonal portion near the end thereof for sliding engagement with the stick section 2.

Dome ribs 5 are hinged to a crown 4 fixed to the stick section 2. Stretcher members 7 are hinged at 8 to the dome ribs 5 and at their other ends, the stretcher members 7 are hinged to a sliding runner 6. Struts 10 are hinged to an auxiliary runner 11 fixed to the end of the stick section 3. The struts 10 are, themselves, hinged at 9 to the stretcher members 7. The stick 1 includes a tip 13 which is reinforced and which is adapted to engage fixed objects, such as the ground 14. The other end of the stick includes a handle 12 connected to the stick section 3 by an extension 3'.

A compression spring 15 is provided in the section 2 and is fixed at one end thereof. The other end of the spring 15 engages a platform 16 on the end of a rod 17. The rod 17 extends through the stick sections and is fixed within the stick section 3 by means of a lateral anchor pin 18.

A resilient locking pawl 19 is provided within the stick section 3 and is attached to the stick section by means of projections 45 and 44 engaging discrete apertures in the stick section 3. The other end of the pawl 19 includes a locking head 41 having a locking nose 27 with a sloped edge and an under-edge forming a shoulder which is normally at 90° to the axis of the stick. The locking head also has a V-shaped cut-out portion 24 having an inner corner 39 and a shoulder 40 at 90° to the axis of the stick. A sloped cam edge is illustrated at 24 in this cut-out portion. Finally, the locking pawl 19 is provided with a push-button 20 on a stem 38 extending out of the stick from the pawl portion 28.

A second locking pawl member 21 is provided in the stick section 2 and is anchored to the section 2 by means of projection 33 engaging a discrete aperture in

the stick section. The locking pawl 21 includes a locking head having shoulders 127 and 128. The edges leading to the shoulders 127 and 128 are sloped at 126, for instance, and include opposed edges at 90° to the axis of the stick 1 defining a cut-out portion in the locking head. Corresponding apertures 29 and 30 in the stick section 3 and 31 and 32 in the stick section 2 are adapted to coincide when the stick sections are extended, such as shown in FIGS. 2 and 3, and the locking shoulders 127 and 128 are adapted to project through the openings to maintain the stick sections in their locked extended position. The locking pawl 21 is normally held in a locked position by means of a double spring 35 which passes through an opening 36 in the locking pawl. The double spring 35 is shown in FIG. 5 having legs on either side of the locking pawl 21. A floating connecting blade member 22 is provided in the stick and includes an angled portion 23 engaging the cut-out portion 24 and at the other end thereof. There is provided an angled member 25 adapted to engage the sloped surface 26 of the locking pawl 21.

In operation, if the umbrella is in a closed position, such as shown in FIG. 1, the locking pawl 21 will be in a locking position, as shown in FIG. 2. If it is required to open the umbrella, the push-button 20 is depressed, whereby the camming sloped edge 24 in the cut-out portion 24 will engage the bent angled member 23 of connecting member 22, forcing it downwardly into a position shown in FIG. 3. When the connecting member 22 is forced downwardly by means of the cam surface 24, the angled member 25 will ride on the cam sloped surface 26 of the locking pawl 21, forcing it inwardly into a position shown in FIG. 3, thereby disengaging the shoulders 127 and 128 from the apertures 29 and 30 of the umbrella stick section 3. The umbrella is now in a condition for telescoping the stick and the stick tip 13 can be pressed against a fixed object 14. A force P will cause the stick section 2 to telescope within the stick section 3 compressing the spring 15, thereby loading it. An aperture 42 in the stick section 2, near the end 2' thereof, will be engaged by the locking shoulder 27 of the locking pawl 19, thereby retaining the stick section 2 in its telescoped position as shown in FIG. 4 and keeping the spring 15 in a loaded compressed state.

Of course, as is known, the telescoping of the stick sections 2 and 3 will force the dome ribs 5 to pivot to an umbrella erect position.

When it is required to close the umbrella, the control push-button 20 is again depressed, thereby disengaging the shoulder 27 from the stick section 2, whereby the spring 15 will allow the umbrella stick sections 2 and 3 to extend fully until the apertures 31 and 32 of the stick section 2 will coincide with the apertures 29 and 30 of the stick section 3. The spring 35 will cause the

locking pawl 21 to move radially, forcing the shoulders 127 and 128 to engage and lock within the apertures 29 and 30, thereby retaining the umbrella stick sections 2 and 3 in their extended position.

5 In this locked position, the umbrella is closed, and the umbrella stick can be used as a walking stick, without fear of accidental telescoping of the sticks.

I claim:

1. An umbrella frame comprising an umbrella stick, 10 a crown at one end of the stick and a handle at the other end, dome ribs hinged to the crown, with at least a first telescopic section at the handle end and a second telescopic section at the crown end, at least a runner fixed to the first section and support members hinged to the runner and to the dome ribs, a compression spring means provided between the sections, a first locking means for locking the umbrella stick sections in their telescoped loaded position, control means for disengaging the locking means to unlock the stick sections and allow the sections to extend under the influence of the spring means, second locking means adapted to lock the umbrella stick sections when the stick sections are in their extended position, and connecting means between the control means and the second locking means to disengage said locking means to allow the umbrella stick sections to telescope when a preselected force is axially applied to the umbrella stick against the urging of the compression spring.

2. An umbrella frame as defined in claim 1, wherein 30 the first locking means includes a resilient pawl within the first stick section having a shoulder projection adapted to engage a seat in the second stick section when the umbrella stick sections are telescoped, and said resilient pawl includes a projection extending outwardly of the stick having a push-button on said projection as said control means for disengaging the resilient locking means from the seat defined in the telescoped sections.

3. An umbrella frame as defined in claim 2, wherein 40 the second locking means includes a spring-urged pawl in the second section having locking projections adapted to engage seats in the first and second sections when the umbrella stick is extended for locking the sections in their extended position.

4. An umbrella frame as defined in claim 3, wherein 45 the connecting means includes an elongated floating member and a cam surface associated with the first locking means for moving the connecting means axially when the control means is depressed and a cam surface 50 provided on the second locking means, whereby the connecting means acting on the cam surface of the second locking means will force the second locking means inwardly, thereby disengaging the locking projections from the seats in the first and second sections.
